BALL HOUSING FOR AN AQUARIUM FILTER

Monte L. Levin, New York, N.Y., assignor to
Metaframe Corporation, Maywood, N.J.

Filed Apr. 24, 1972, Ser. No. 247,230

Term of patent 14 years

Int. Cl. D23—01

U.S. Cl. D23—4

FIG. 1.

FIG. 2.

FIG. 3.

FIG. 4.

FIG. 1 is a front perspective view of a ball housing for an aquarium filter showing my new design;

FIG. 2 is a rear perspective view thereof;

FIG. 3 is a top plan view thereof; and

FIG. 4 is a bottom plan view thereof.

I claim:

The ornamental design for a ball housing for an aquarium filter, substantially as shown.
